UNITED STATES PATENT OFFICE.

FREDERICK A. PALMER, OF MIDDLETOWN, CONNECTICUT.

MATTRESS-GUARD.

1,080,845.

Specification of Letters Patent.

Patented Dec. 9, 1913.

Application filed October 6, 1913. Serial No. 793,665.

To all whom it may concern:

Be it known that I, FREDERICK A. PALMER, a citizen of the United States of America, and resident of Middletown, in the county 5 of Middlesex and State of Connecticut, have invented certain new and useful Improvements in Mattress-Guards, of which the following is a specification.

This invention relates to certain new and 10 useful improvements in mattress guards and it has for its objects among others to provide a simple, cheap and light mattress guard or pocket corner which can be readily applied or detached at will and which 15 will serve to keep the mattress from sliding either way, that is laterally or endwise. The device may be attached in any suitable manner and may be foldable in its nature or with one or both of its parts substantially rigid. When made foldable, it occupies but little space in storing or in shipping.

Other objects and advantages of the invention will hereinafter appear and the 25 novel features thereof will be particularly pointed out in the appended claims.

The invention is clearly illustrated in the accompanying drawings, which, with the numerals of reference marked thereon, form 30 a part of this specification, and in which—

Figure 1 is a perspective view showing the application of my present improvement. Fig. 2 is a top plan view of Fig. 1. Fig. 3 is a view showing the guard or pocket corner folded. Fig. 4 is a perspective view of a modified form.

Like numerals of reference indicate like parts throughout the several views.

The guard may be constructed of any 40 suitable material and may assume any desired form applicable for holding the mattress at the corner of the spring frame.

In Figs. 1, 2 and 3 I have shown the guard as composed of two members 1 and 2 movably united in any suitable manner, as at 3, the two members 1 and 2 adapted to extend at right angles to each other and to be disposed vertically when in position for use, as seen in Fig. 1. When not in use, or when 50 stored or ready for shipment, the members are folded flat upon each other, as shown in Fig. 3, occupying but little space.

When applied, the guard or pocket corner 55 may be affixed in position in any suitable manner; for instance in Fig. 3 I have shown

the member 1 as provided at its lower end with vertical slots 4, of which there may be one or more, terminating at the upper end in a horizontal slot 5 adapted to receive headed pins or analogous means 6 secured to the angle member 7 of the spring frame. This, however, is but one form of means that may be employed for the ready attachment and detachment of the guard. The mode of application will be apparent. The member 1 is placed so that the open ends of the slot 4 are in position to receive the pins. The member 1 is then pushed downward until the pins are in alinement with the horizontal portions of the slots and the member 1 then moved in the direction of the arrow in Fig. 1 and the guard thus held fixedly in position. The member 2 is swung at a right angle to the member 1 and then affixed in any suitable manner to the spring 75 8, in this instance being shown as attached thereto by means of a hooked wire or the like 9 engaging in an opening 10 in the free end of the member 2 and with one of the wires of the spring. When in this position, the guard serves to hold the mattress against movement in either direction. In practice, it would be advisable to have one of these guards at each corner of the mattress, although such is not essential. As seen in 80 Figs. 1 and 3, the member 1 is of greater height than the member 2 forming the extension 11 which may bear against the vertical portion of the flanged member 7 and thus brace the guard.

In Fig. 4 I have shown the device with both members 1^a and 2^a rigid, the member 1^a being provided with openings 12 for the passage of screws, nails or other means, and the free end of the member 2^a provided with 95 an opening 13 for the reception of means which may be employed for securing it in position, such for instance as the hook 9 shown in Figs. 1 and 3. This form also is provided with the downward extension 11^a 100 for the same purpose as the extension 11 in Figs. 1 and 3.

The outer corners of the members 1 and 2 may be tapered or beveled, as seen at 14 in both forms for appearance sake and at the 105 same time slightly decreasing the weight of the guard.

It will be evident that if desired the member 2, in the form where the guard is shown as composed of two hinged members, may 110

be folded flat against the member 1 without detachment of the latter from the mattress frame.

Modifications in detail may be resorted to 5 without departing from the spirit of the invention or sacrificing any of its advantages.

What is claimed as new is:—

- 10 1. A corner attachment for mattresses embodying members adapted to extend at substantially right angles to each other, and having means for attachment to a mattress support and means for attachment to a bed-bottom-fabric.
- 15 2. A corner attachment for mattresses embodying members adapted to extend at substantially right angles to each other, and having means for attachment to a mattress support and means for attachment to a bed-bottom-fabric, one of said members being 20 rigid.
3. A corner attachment for mattresses embodying members adapted to extend at substantially right angles to each other, and

having means for attachment to a mattress 25 support, one of said members being rigid and the other movably connected thereto.

4. A mattress attachment comprising members disposed at substantially right angles to each other, one of said members 30 having means for attachment to a member of a spring frame and the other provided with means for attachment to a bed-bottom-fabric.

5. A mattress attachment comprising 35 members disposed substantially at right angles to each other, one of said members having means for attachment thereof to a bed-bottom-fabric and the other member having a downward extension provided with 40 means for its attachment to a member of the bed-bottom frame.

Signed by me at Middletown, Conn. this 4th day of October, 1913.

FRED'K A. PALMER.
